CLAIM

The ornamental design for a table lamp, as shown and described.

DESCRIPTION

FIG. 1 is a right rear perspective view of a table lamp according to my new design;

FIG. 2 is a left rear perspective view thereof, with the tape measure portion extended as compared to FIG. 1;

FIG. 3 is a top plan view thereof, showing a first switching position of the lamp housing on its base;

FIG. 4 is a front elevational view, from the left in FIG. 3;

FIG. 5 is a side elevational view, from below in FIG. 3;

FIG. 6 is a side elevational view, from above in FIG. 3; with the tape measure portion rotated downwardly and the lamp housing in a second switching position;

FIG. 7 is a rear elevational view; and,

FIG. 8 is a bottom plan view thereof.
